UNITED STATES PATENT OFFICE.

JAMES T. HOGAN, OF JERSEY CITY, NEW JERSEY, ASSIGNOR TO THE NATIONAL MACHINE COMPANY, A CORPORATION OF NEW YORK.

BUTTONHOLE-SEWING MACHINE.

SPECIFICATION forming part of Letters Patent No. 710,149, dated September 30, 1902.

Application filed March 13, 1899. Serial No. 708,801. (No model.)

To all whom it may concern:

Be it known that I, JAMES T. HOGAN, a citizen of the United States, residing in Jersey City, county of Hudson, and State of New Jersey, have invented a new and useful Improvement in Buttonhole-Sewing Machines, of which the following is a full, clear, and exact specification.

My invention relates to buttonhole-sewing machines. In prior machines of this class the barring-strokes have been made parallel with the side stitches; but in the finer grades of work it is preferred to have the barring-strokes at right angles to the side stitches. Such work has been done by hand, requiring skilled labor and taking considerable time.

By my invention I am enabled to sew a complete buttonhole by machine-stitching, with the barring-strokes at right angles to the side stitches.

To carry out my invention, I employ a work-carrying plate which rests upon the base-plate of the machine and is fed by suitable means to form a side row of stitches. This plate is then turned at right angles to its former position and fed while in such position back and forth to form barring-strokes. It is again turned at right angles to its last position and the other row of side stitches formed and finally turned to form the second set of barring-strokes.

My invention also comprises a novel form of work-carrying plate.

In the accompanying drawings, forming a part of my specification, similar characters of reference indicate similar parts in the several views.

Figure 1 is a side elevation of the entire machine, a part of the bottom frame being broken out. Fig. 2 is a front elevation, a cover-plate being removed to show the needle-bar-carrying mechanism. Fig. 3 is a top view of the cloth clamp and carrier and part of the base-plate, a part of the clamp being broken to show the shape of the aperture in the carrier-plate. Fig. 4 is a top view of a part of the main arm of the machine, showing mechanism for operating the needle-bar carrier, thread-guide bar, and cloth-cutter. Fig. 5 is an inverted plan of the mechanism below the base-plate for feeding the cloth-carrier. Fig.

6 is a longitudinal section on the line 6 6 of Fig. 5. Fig. 7 is a longitudinal section on the line 7 7 of Fig. 5. Fig. 8 is a top view of a modified form of clamp and carrier-plate. Fig. 9 is a vertical transverse section on the line 9 9 of Fig. 8, the clamp being shown in a different position. Fig. 10 is an inverted plan view of the carrier-plate of Fig. 8. Fig. 11 is a top view of parts of the clamp in a position after spreading the buttonhole-slot. Fig. 12 is a horizontal section on the line 12 12 of Fig. 7.

My invention may be attached to any style of machine having a vibrating needle-bar. I have shown it in connection with a purl-stitching machine in which A is the arm; J, a connecting-rod to the toothed segmental plate K², which latter engages a toothed wheel k to rock the looper J².

J' is the needle-bar; J³, the shuttle mechanism.

K is a slotted segment to which is secured a pitman K' to actuate the needle-frame to vary the bight of the stitch.

L is a cam to actuate the slotted segment K and the connecting-rod J.

C represents an arm carrying a knife-edge c² and is pivoted to the base-plate at c'. When swung into a horizontal position to cut a buttonhole-slit, it is depressed and forced into the fabric by turning the cam-face c by the handle C' under the roller C². None of these parts, however, form any part of my invention.

I will first describe the brake and belt-shifting mechanism, although the same is not claimed herein, as it forms the subject-matter of an application filed by me June 30, 1899, Serial No. 722,398. Located below the base-plate of the machine and supported so as to slide freely in suitable brackets is a bar E, held normally in position by a spring e'. As shown, this spring is held on the bar between a ring e², secured thereto, and a supporting-bracket e³ of the frame, although any other arrangement of spring to accomplish this purpose may be employed. To the head e of the bar E are attached two slotted arms G and G' by means of set-screws g⁴ and g⁵, respectively. These arms are pivoted at g² and g³, respectively, to a bracket H of the frame of

the machine. The end of arm G is provided with a brake-shoe g , which bears against a cam-face i on the disk I, forming part of the fast pulley D' on the main shaft A'. D is a loose pulley on said shaft, and the belt g^6 is shifted from one pulley to the other by the movement of the arm G' and its belt-shipping fork g' .

Rigidly secured to the bar E is a collar f^3 , to which is pivoted an arm F at f' of an ordinary toggle-joint, the other arm, F', being pivoted to a bracket f^4 at f^2 , depending from the base-plate. To the hook F², secured to the ends of the stud uniting the two inner ends of the arms F and F', is attached a strap or cord which is under the control of the operator. The screw F³ passes through the arm F' and limits the throw of the toggle by bearing against the bar E. The operation of my improved brake and belt-shipping mechanism is as follows:

In starting the machine the operator by pulling on the strap attached to the hook F² and holding the same moves the bar E to the right, thus releasing the brake-shoe g from contact with the cam-surface of disk I and shifting the belt g^6 to the fast pulley D'. When the operator has completed his work, the strap is released and the spring e' throws the bar E to the left, which brings the brake-shoe g into position and shifts the belt g^6 to the loose pulley D through the arms G and G', respectively. The cam-surface i is so placed on the surface of the disk I that it frictionally engages the brake-shoe g at the moment the needle-bar is at its highest position or at a point that the needle may clear the work, thus relieving the operator of the necessity of turning the shaft to release the work.

The brake mechanism not only serves to arrest the movement of the driving-shaft, but also as a positive locking device to prevent rotation until the bar E is moved forward by the toggle-joint.

I will now describe my improved clamp and cloth-carrier and the mechanism by means of which I am enabled to sew a row of side stitches and a set of barring-stitches at the end of a buttonhole at right angles to the side stitches.

B designates a work-carrying plate adapted to rest upon the base-plate A² of the machine. It is cut away at b^2 , where it rests over the slot t^3 in the throat-plate. The work is held onto the plate B by a clamp T, the forked ends of which are supported on studs b^3 , projecting upward from a bracket b^4 , secured to the plate B.

t designates a cam-lever pivoted to a stud t^2 , affixed to a post t^8 , and which carries a cam-face t^4 , which bears against the upper face of clamp T to force it down onto the cloth when the lever t is turned down. Upon releasing the cam the clamp T is thrown up by springs b^{12} , surrounding the studs b^3 and bearing against the under face of the ends of the

clamp. Pins b^8 , inserted into the upper ends of the studs and projecting from one side thereof only, tend to cause the free end of the clamp to tilt up against the handle t. The clamp T is cut similarly to the carrier-plate to permit the passage of the needle and has secured thereto serrated plates t' , (shown in Fig. 2,) which take into the cloth when the clamp is lowered and hold it firmly in position.

The plate B is provided on its sides 1 and 3 with racks b b' to engage a toothed wheel B², held frictionally on a stud n , by which means the carrier-plate is fed to form the side rows of stitches, as will be hereinafter more fully explained. The plate B is recessed at b^6 and b^7 on sides 1 and 3 and at b^9 and b^{10} on sides 2 and 4. When in position to sew a buttonhole, the plate B rests against a guide-plate B', secured to the base-plate of the machine, and cut into sections, as shown, to receive the toothed wheel B² and permit the projection of a finger r from beneath the base-plate. This guide-plate carries a gage-shoulder B³, which projects into the recesses b^7 and b^9 , which recesses determine the length of travel of the work-carrying plate B during the formation of the side and barring stitches. The recesses b^7 on the sides 1 and 3 are cut the desired length of the buttonhole, and b^9 on the sides 2 and 4 the length of the barring at the ends. The recesses b^6 on the sides 1 and 3 are cut merely to provide a clearance for the finger r , as this latter during the formation of the side stitches remains inactive. During the formation of the barring-stitches the finger r engages one or the other of the notches B⁴ in the sides 2 and 4 of the plate B to feed said plate in the manner hereinafter described. At such time the toothed wheel B² projects into one of the recesses b^{10} on the sides 2 and 4 and is of course then inactive. The plate B is not necessarily in the form of a square or parallelogram, and my invention is not limited to forming barring-stitches at an exact right angle to the side stitches. If the angle is to be greater or less than a right angle, the ends 2 and 4 of the carrier-plate B are made with the angle desired with reference to the sides 1 and 3.

The mechanism by which the carrier-plate B is fed is preferably located beneath the base-plate of the machine.

n^3 designates the end of a vertical shaft which is geared to and driven by the main shaft A', as will be readily understood. The shaft n^3 carries a cam O⁴, which supports the forked end m m' of a lever M. It also carries a crank-disk O, from which extends a pitman O² to actuate the shuttle mechanism J³. The lever M is fulcrumed on a stud m^3 , extending from the base-plate, and at its outer end is slotted at n^2 and has secured thereto by means of a set-screw n^5 a similarly-slotted lever M', which latter is pivoted on the hub of ratchet-wheel N, which surrounds the stud n . By adjusting the screw n^5 in the slot n^2 of

the levers M and M' the pawl m^2 , secured to the lever M', which engages the teeth of the ratchet-wheel N, mounted on the stud n, is given a greater or less throw, thus enabling me to make a fine or coarse stitch or to vary the distance between the stitches for any given length of buttonhole. The stud n projects up through the base-plate and carries the toothed wheel B², which engages the racks b b' of the work-carrier plate B, as before described. The toothed wheel B² is in frictional contact with the stud n, a washer n⁴ being interposed between the head of the stud and the wheel B², so that the operator is enabled to place the carrier-plate B on the base-plate of the machine in engagement with the wheel B² when the needle is in any position, and by simply moving the carrier-plate by hand is enabled to bring it to the end of the buttonhole to begin the sewing of the side stitches.

The lever M has pivoted thereto at its outer end at p' a link P, which latter at its other end is pivoted at p to a pawl carrier-plate Q', pivoted on a stud q⁶. q' designates a pawl on this plate, and which drives a ratchet-wheel Q, mounted to rotate on said stud q⁶. A spring q² holds the pawl in engagement with the ratchet-wheel. Secured to the latter by suitable means, such as a screw q⁷, is a cam q, which bears against a pin q⁸, fixed to an arm R, pivoted to the base-plate at r'. The other end of arm R is formed into the upturned finger r, which projects through the base-plate and is turned down thereon to engage the notch B⁴ of the carrier-plate B. The pin q⁸ is held in positive engagement with the cam q by means of a spring q⁴.

Although the link P is reciprocated at all times by the oscillation of lever M, the ratchet-wheel Q must remain inactive during the formation of the side stitches, and for this purpose one tooth of the said wheel is omitted at the space q⁵. This permits the pawl q' to ride over the plain face of the wheel at q⁵ during the period when the rack of carrier-plate B is engaged with the toothed wheel B² to form the side stitches. When the end of the buttonhole is reached and the barring stitches are to be made, the ratchet-wheel Q is advanced one tooth by means of the plate S. This plate is slotted and may be readily moved on the supporting-screws s' s². It is normally held out of engagement with the wheel Q by the spring S². When it is desired to advance the wheel Q one tooth, so that it may be operated by the pawl q', the operator pushes the handle S', which projects from the plate S through an opening in the base-plate of the machine, to the left, thus bringing the finger s³ into contact with a tooth of wheel Q and advancing it to that extent, the plate S being then retracted by the spring S². The pawl q' then rotates the wheel Q during the formation of the barring-stitches and until the plain portion q⁵ of the face of wheel Q is brought opposite the pawl q',

when said wheel again becomes inactive during the formation of the other row of side stitches or until the end of the buttonhole-slit is reached.

The operation of the mechanism above described is as follows: The work is first clamped to the plate B by the clamp T. The cutter-lever C is then turned down on the pivot c', as shown by the broken dotted lines in Fig. 1. 75 Then by turning the cam c by means of a handle C' under the roller C² the buttonhole will be cut by the knife-edge c². The plate or work-support rests on the bed-plate of the machine when the buttonhole is cut, after 80 which operation the plate or support is pushed into position under the needle, as shown in Figs. 1 and 3, with the rack b in engagement with the toothed wheel B². The operator then releases the brake-shoe g and at the same 85 time shifts the belt g⁶ from the loose pulley D to the fast pulley D' through the operation of the toggle-joint, as before described. Motion being imparted to the main shaft A', it is transmitted to the shaft n³ and by cam O⁴ 90 to lever M. The oscillation of the latter actuates the pawl m², and thus the ratchet-wheel N and toothed wheel B², which feeds the plate B in the direction of the arrow, Fig. 3, to form the side stitches. As shown in 95 said figure, the parts are in position after several side stitches have been made. The length of buttonhole that can be sewed is determined by the recess b⁷, and when the shoulder B³ contacts with the end wall of this recess the end of the buttonhole has been reached. During this time the pawl q' rides over the plain face q⁵ of the ratchet-wheel Q, so that no movement is imparted to the finger r. To now form the barring-stitches across 105 the end of the buttonhole-slit, the carrier-plate is raised by hand and turned with its side 2 against the guide-plate B'—that is, at right angles to its former position—so that the finger r will engage the notch B⁴. The 110 shoulder B³ will fall into recess b⁹ and toothed wheel B² into recess b¹⁰. The operator then advances the ratchet-wheel Q one tooth by moving the plate S. The needle at this time is at the center of the buttonhole-slit, and by 115 the rotation of ratchet-wheel Q by means of the pawl q', the cam q and the arm R, whose finger r engages plate B, the said plate is fed first to one side or the other to sew a line of stitches as far as desired, then back across the end of the 120 slit to the desired distance on the other side, and finally back to the center of the slit, the cam q being so constructed as to accomplish these movements of the work-carrier plate. This completes the barring-stitches and brings 125 the plain part q⁵ of wheel Q opposite the pawl q'. The carrier-plate is then raised to bring the side 3 against the guide-plate B' to sew the other row of side stitches and finally is again turned to bring the side 4 into position to sew 130 the barring-stitches at the other end. During the formation of the barring-stitches it

will be noticed that the toothed wheel B^2 falls into the recess b^{10} , and although it continues to rotate it performs no work.

In Figs. 8, 9, 10, and 11 I have shown a modified form of work-carrier plate. The clamp-plate T instead of being formed in one integral piece is split along its central line T' , so as to form separable branches or legs, the purpose being to spread the cloth after it has been cut, so that the needle may not gather up the frayed edges of the buttonhole-slit. t^7 is a post seated to rotate in plate B and having its lower end made oval in section to serve as a cam-surface. The head t^8 of this post carries the forked ends of a handle t , the lower edge of each fork being formed into a cam-surface, which when the handle t is turned down on the washer t^9 clamps the work between the plates B and T . After the work W is thus secured the buttonhole-slit is cut and then the handle turned so that the cam-surface of the post t^8 , acting against the bracket-pieces t^5 , attached to the separable parts of clamp T , spreads such parts to open the buttonhole-slit, as shown in Fig. 11. The means above described form a simple and compact arrangement to clamp the work to the carrier-plate and also to separate the parts of the clamping-plate by a simple movement of the handle t . I have also shown in these figures a form of work-carrier plate which does not require to be lifted at the end of a row of side or barring stitches, as in the form first described. The plate B instead of having racks, recesses, and notches on its edges to engage with the feed mechanism has its edges straight. On the under face of this plate I secure a rack B^{10} , made straight on the sides 1 and 3, Fig. 10, for a length sufficient to complete the feed for the side stitches and at the ends 2 and 4 for a length sufficient to complete the feed for the barring-stitches. Between the points 6 and 7 the rack is an arc of ninety degrees described from the point 5, so that the plate may be carried around from one position to a position at right angles thereto. B^2 is a toothed wheel in frictional engagement with stud n and driven by the ratchet-wheel N , as before described, or any other suitable mechanism and which engages the feed-wheel B^5 through the intermediate pinion B^6 to feed the work-carrier plate B during the formation of both side and barring stitches. The toothed wheel B^5 is mounted loosely on a stud in the base-plate of the machine, and its function is to feed the straight parts of the rack and then turn the work-carrier plate from one position to a position at right angles thereto. The latter is done at the end of each row of side and barring stitches by stopping the machine and manually operating the wheel B^6 by turning the same by the handle B^8 . The rack being on the under face of plate B admits of the corners of said plate when turned to pass over the wheels B^2 and B^5 . The plate B is grooved on its under face at B^7 to correspond with the

form of the rack. Instead of being formed by a plate B^9 , as shown in Fig. 10, a narrow bar would suffice for the purpose. This groove 70 engages a pin V , fixed in the base-plate of the machine and which keeps the work-carrier plate in operative position. The pin V is located directly opposite the center of the wheel B^5 , so as to guide the plate B and hold the entire rack, straight and curved parts, in constant mesh with the wheel B^5 . In this modification the length of the side and barring stitches is regulated by the operator and not by the length of straight portion of rack, 80 which has surplus travel both ways for convenience of operating.

In the position shown in Fig. 8 a row of side stitches is being formed. As soon as the plate is automatically fed to the end of the straight 85 portion of the rack on side 1 by means of the wheels B^2 B^5 B^6 it is turned manually by means of the hand-wheel B^6 , so as to bring the straight portion on the side 2 into position to form the barring-stitches. The plate is then 90 automatically fed by gears B^2 B^5 B^6 to form a row of barring-stitches across the end of the buttonhole-slit at right angles to the side stitches. At the end of the barring operation the plate is again manually turned by the 95 wheel B^6 to bring the side 3 of the rack into position to be fed by the wheels B^2 B^5 B^6 to form the other row of side stitches and is finally turned to bring the side 4 of the rack into position to form a row of barring-stitches 100 at the other end of the buttonhole-slit. By this mechanism it will be seen the operator is not required to lift the work-carrier plate at the end of the formation of a row of side or barring stitches, but that the plate remains at all 105 times on the base-plate of the machine.

Having now described the nature of my invention, what I claim as new, and desire to secure by Letters Patent, is—

1. In a buttonhole-sewing machine the combination with stitch-forming mechanism, of a work-support comprising a substantially rectangular plate having racks on a portion of two of its edges and notches in the two other edges, a pinion to engage said racks, a finger 110 to engage said notches, and means to actuate said pinion and finger substantially as described.

2. In a buttonhole-sewing machine adapted to sew side stitches and barring-stitches, the combination with stitch-forming mechanism of a work-support comprising a substantially rectangular plate having racks on a portion of two of its edges, a pinion to engage said racks, a plate carrying a finger to engage suitable notches in the two other edges of the work-support, a cam and ratchet-wheel to actuate said plate, and means to throw said ratchet-wheel into operative position, when the work-support is adjusted to sew barring- 125 stitches.

3. In a buttonhole-sewing machine adapted to sew side stitches and barring-stitches, the combination with stitch-forming mechanism

of a work-support comprising a substantially rectangular plate having racks on two of its edges, a pinion to engage said racks, means to rotate said pinion, a plate having a finger 5 to engage notches in the two other edges of the work-support, a ratchet-wheel and cam to actuate said plate, said wheel being so constructed as to be inoperative during the formation of side stitches, and means to throw it 10 into operative position when barring-strokes are to be formed.

4. In a buttonhole-sewing machine the combination of a work-carrier plate, a driving shaft, a cam on said shaft, a lever oscillated 15 by said cam, a link connected to said lever, a pawl-carrier plate connected to said link, a pawl on said plate, a ratchet-wheel engaged by said pawl, a cam connected with said ratchet-wheel, an arm actuated by said cam, 20 and engaging the work-carrier plate, substantially as described.

5. In a buttonhole-sewing machine the combination with stitch-forming mechanism, of a work-support comprising a substantially rectangular plate having racks on a portion of 25 two of its edges, a pinion to engage said racks, a driving-shaft, and adjustable levers actuated by said shaft and connected by intermediate mechanism to said pinion whereby the 30 number of stitches to a given length of feed may be varied, substantially as described.

6. In a buttonhole-sewing machine the com-

bination with stitch-forming mechanism, of a work-support comprising a substantially rectangular plate having racks on a portion of 35 two of its edges, a pinion to engage said racks, a ratchet-wheel to actuate said pinion, a driving-shaft and adjustable levers intermediate 40 said shaft and ratchet-wheel to drive the latter, substantially as described.

7. In a work-carrier plate for sewing-ma- chines, the combination of a lower plate, an upper clamping-plate, supported by studs on the face of the former plate, and a spring sur- 45 rounding each of said studs, and bearing against the under side of the upper plate, to normally hold it out of contact with the lower plate, substantially as described.

8. In a work-carrier plate for sewing-ma- chines, the combination of a lower plate, an 50 upper clamping-plate supported by studs on the face of the former plate, a spring sur- rounding each of said studs, and bearing against the under side of the upper plate to normally hold it out of contact with the lower 55 plate, and means to tilt the free end of the clamp, substantially as described.

In testimony whereof I have signed my name to this specification in the presence of two subscribing witnesses.

JAMES T. HOGAN.
